UNITED STATES PATENT OFFICE.

HENRY E. LEPPERT, OF NEW BRITAIN, CONNECTICUT, ASSIGNOR TO THE HART MANUFACTURING COMPANY, OF HARTFORD, CONNECTICUT, A CORPORATION OF CONNECTICUT.

TURN-BUTTON FOR ELECTRIC SWITCHES.

No. 874,016.

Specification of Letters Patent.

Patented Dec. 17, 1907.

Application filed October 29, 1904, Serial No. 230,460.

To all whom it may concern:

Be it known that I, HENRY E. LEPPERT, a citizen of the United States, residing at New Britain, in the county of Hartford, State of Connecticut, have invented certain new and useful Improvements in Turn-Buttons for Electric Switches, of which the following is a full, clear, and exact description.

My invention relates to turn buttons for electric switches and particularly to certain improved features of construction over those set forth in United States Letters Patent No. 578,695 of March 9, 1897.

The object of the invention is to simplify and render more economical the manufacture of such devices.

In the accompanying drawings, Figure 1 is a vertical section of my improved turn button, certain parts being partly in elevation. Fig. 2 is a view of the inner end of the turn button; the spindle, spring and spindle retainer being removed. Fig. 3 is a side elevation of the spindle shell. Fig. 4 is a side elevation of the spindle or spindle head partly in section. Fig. 5 is an end elevation of the spindle retainer.

1 is a handle or turn button which may be of any suitable design and which is preferably formed from insulating material.

2 is the spindle head by which the handle may be detachably secured to the well known center post or spindle of a switch. 2^a represents in dotted outline the threaded end of a portion of said center post. 2^b is a shoulder or abutment formed on the spindle head 2, the same preferably being of hexagonal outline.

3 is a shell, the cross-sectional outline of the bore of which may so correspond to the outline of the shoulder 2^b on the spindle head, that when the spindle 2 is inserted into the shell 3 it may slide longitudinally but will not turn independently thereof. In the external surface of the shell 3 nibs or indentations 3^b may be formed to afford anchorages for the material of the button 1 which is preferably molded around said shell.

4 is a spring located outside of the spindle head 2.

5 is a retaining piece preferably in the form of a washer having a groove therein formed at an angle with the face of the washer as best seen in Fig. 1 and arranged to receive the edge 3^a of the shell 3.

In assembling the parts the handle 1 is pref-

erably molded around the shell 3; the spindle head 2 is inserted and the spring 4 slipped into place. The retaining member 5 is then finally applied. Obviously, when the member 5 is pushed down on the edge 3^a of said shell, said edge will be expanded or forced outwardly so as to follow the groove and form in effect a rivet which firmly unites the parts. The spring 4 takes up against the shoulder or abutment 2^b at one end, the latter performing the function of an abutment as well as a retaining member. The tendency of the spring 4 is to normally hold the spindle head 2 in the position shown in Fig. 1. When the turn button is attached to the switch, it is screwed down on the center post 2^a until it takes a firm seat. Usually the length of the center post 2^a is such that the spindle head 2 will not be seated thereon until the spring is under slight tension. Ordinarily switches are provided with covers (as shown in the aforesaid patent) and when the turn button is applied, the handle 1 will encounter the cover before said spindle head is entirely seated. The result is that any further rotation of the turn button will cause the spindle head 2 to advance in the handle 1, thus putting said spring 4 under compression and holding the handle snugly against the outer wall of the cover.

In the drawings I have not illustrated the switch cover or the details of the switch because the same are well understood and may be seen upon reference to the above-mentioned patent.

Obviously the angle of the annular groove in the retainer 5 might be reversed if desired. The washer 5 might also be made of two pieces instead of one as shown.

What I claim is:—

1. In a device of the character described, a turn button or key, a cavity therein and extending only partially through the same, a spindle head slidable in said cavity and means to prevent the independent rotation of said key and spindle head, an abutment on the inner end of said spindle head, a second abutment at the inner end of said key, a spring located between said abutments and around said spindlehead.

2. In a device of the character described, a turn button or key, a cavity therein, a shell fixed within said cavity, a spindle head slidable therein, means for preventing the

independent rotation of said shell and spindle head, a shoulder or abutment on said spindle head within said shell, a second shoulder or abutment secured to the outer end of said shell and forming an inwardly projecting shoulder or abutment, a spring between said abutments acting to press said spindle head into said key.

3. In a device of the character described, a turn button or key, a shell fixed therein, a passage in said shell of angular cross-section, a spindle head longitudinally movable in said shell, an abutment at the inner end of said spindle head of an outline corresponding to the cross-sectional outline of the interior of said shell, a second abutment or shoulder projecting inwardly from said shell and a spring arranged between said abutments and normally pressing said spindle head into said shell.

4. In a device of the character described, a key; a cavity therein, a shell anchored in said cavity against independent movement relatively to the key, a spindle head longitudinally movable in said shell but held against independent rotation relatively thereto, an outwardly projecting shoulder or abutment on said spindle head at or near its inner end, an inwardly projecting shoulder or abutment on said shell at or near its outer end, an expansion spring arranged between said spindle head and shell, the ends of said spring engaging said abutments and normally projecting said spindle head into said shell.

5. In a device of the character described, a handle or key, a cavity therein, a shell fixed in said cavity, a spindle head longitudinally movable in said shell, an outwardly extending abutment at the inner end of said spindle head, a retaining device for said spindle head secured to the outer edge of said shell and forming an inwardly projecting shoulder relatively thereto of smaller diameter than the shoulder on said spindle head, a spring located between said shoulder on the spindle head and said retaining member.

6. In a device of the character described, a turn button or key, a cavity therein, a spindle head slideable in said cavity and means to prevent the independent rotation of said key and spindle head; an abutment projecting outwardly from the inner end of said spindle head, a second abutment projecting inwardly from said button or key forming a passage of less diameter than the diameter of the abutment on said spindle head, a spring located between said abut-

ments and pressing said spindle head into said key.

7. A switch handle comprising a body portion, a shell embedded therein, a washer having an inclined groove, the neck of said shell being flared into said groove, a spindle projecting through said washer, a head on the inner end of the spindle and a spring engaging the head and the back of the washer.

8. A switch handle comprising a body portion, a shell embedded therein and having an angular projection with an external notch for interlocking with the body portion, an abutment washer mounted in the body portion at the entrance to the shell, a spindle adapted to extend through the opening in said abutment member, an enlarged head on the inner end of said spindle, and a spring engaging said head and the rear of said abutment member.

9. A switch handle, comprising a body-portion, a cavity in the lower side thereof, a spindle extending into said cavity, means for holding the spindle from rotation relatively to the body-portion, the diameter of the intermediate portion of the spindle being less than the diameter of the cavity to afford room for a spring, an abutment member at the entrance to said cavity, a spring engaging at one end against said abutment and at the other end operating to force the spindle inwardly, said abutment centering and guiding the exposed end of said spindle.

10. A switch handle, comprising a body-portion of insulating material, a cavity in the lower side thereof, a metallic lining therefor, a spindle slideable in said cavity, means for holding said spindle from rotation relatively thereto, an abutment at the entrance to said cavity and reducing the diameter thereof, said abutment being secured to said lining, the body of the spindle being reduced to a diameter less than the diameter of the cavity in which it is located, a spring around said reduced body-portion, said spring bearing at one end against said abutment and operating at the other end to force said spindle into said cavity, said abutment operating to center and guide the exposed end of the spindle.

Signed at Hartford Conn. this 25 day of Oct. 1904.

HENRY E. LEPPERT.
